DOWN-HOLE MOTOR POSITIONING DEVICE

Wallace Clark, Indianapolis, Ind.

Application September 11, 1957, Serial No. 683,425

7 Claims. (Cl. 255—4)

This invention relates to a down-hole motor positioning device. In my copending application, Serial No. 582,016, filed May 1, 1956, I have disclosed well drilling apparatus and methods of drilling wells wherein a hydraulic motor is used at the bottom of the hole being drilled. With such a device, it is necessary that means be provided to position the motor with respect to the casing at the bottom of the hole so as to fix it both against upward thrust, downward thrust and rotational thrust.

It is also necessary to provide means whereby the motor unit may be lowered into the hole and whereby the motor unit may be lifted out of the hole when the situation requires. The particular drilling operation forms no part of the present invention nor does the particular drill bit used. The drill bit, however, should be a collapsible type of drill bit such, for example, as is disclosed in my copending application, Serial No. 683,391 filed September 11, 1957 now abandoned, entitled "Collapsible Earth Drilling Bit."

It is therefore an object of the present invention to provide an apparatus to which a down-hole motor may be secured, the motor preferably carrying a collapsible bit, and which structure as a unit may be lowered into the hole through a casing string. It is another object of my invention to provide a special casing section adapted to be attached to the lower end of a string of well casing having special means for the fixing of the positioning device. It is still another object of the invention to provide a special tool by means of which the assembly may be lowered into the hole until it is fixed in relation to the special casing section, which tool may then be withdrawn from the hole; and to provide a special lifting tool which may be lowered into the hole to pick up the entire assembly so that it may be withdrawn from the hole.

These and other objects of the invention which will be specified in more detail hereinafter or which will be apparent to one skilled in the art upon reading these specifications, I accomplish by that certain construction and arrangement of parts of which I shall now disclose exemplary embodiments.

Reference is made to the drawings forming a part hereof and in which:

Figure 1 is a vertical cross-sectional view of a positioning device according to the present invention suspended from the lowering tool.

Figure 2 is a vertical cross-sectional view through the well casing at the bottom of the hole showing the positioning device in place in the special casing section and showing somewhat diagrammatically the down-hole motor and collapsible bit in drilling position.

Figure 3 is an enlarged fragmentary cross-sectional view taken on the line 3—3 of Figure 2.

Figure 4 is a fragmentary cross-sectional view corresponding to the upper portion of Figure 2, showing the lifting tool in position ready to withdraw the assembly from the hole.

Figure 5 is a horizontal cross-sectional view taken on the line 5—5 of Figure 2.

2

Figure 6 is a similar view taken on the line 6—6 of Figure 2; and

Figure 7 is a fragmentary perspective view of a casing portion.

Briefly, in the practice of the invention I provide a body of such dimensions that it may pass through the well casing and on the body I provide means for attaching a down-hole motor to the lower end thereof. The body is provided with radially pivotable fingers arranged to engage the wall of a special casing section at the bottom of a string of well casing, which section has cooperating elements whereby the body is fixed against rotation as well as against upward or downward movement with respect to the special casing section. In association with the fingers, I provide means for engagement by a lowering tool or a lifting tool alternatively, so that the entire assembly consisting of the positioning device, the down-hole motor and the drill bit may be lowered into position and selectively lifted out from the hole.

Referring now in more detail to the drawings, the body is indicated generally at 10. At its upper end the body is provided with the slots 11 in which the finger members 12 are pivoted as by means of pins 13. The fingers 12 have a particular configuration which will be described hereinafter.

In other slots 14 are mounted the fingers 15 which are pivoted as by means of pins 16. The fingers 15 also have a particular configuration which will be described hereinafter. The fingers 12 and 15 during the lifting and lowering operation are adapted to lie in their innermost position as shown in Figure 1, so that the device may pass through the well casing.

The body 10 is provided with a bore 17 within which the member 18 is slidably mounted. The member 18 has a bore 19 and a helical compression spring 20 is disposed within the bore 19 and extending into the bore 17 so that it tends to urge the member 18 upwardly. The member 18 is provided with the reduced portion 21 providing the annular shoulder 22 and it is also provided with the cylindrical portion 23 having a sliding bearing in a hole 24 in the body 10. The cylindrical portion 23 provides the upper annular shoulder 25.

The plunger, composed of the members 18, 21, 23, is for the purpose of urging the respective fingers 12 and 15 outwardly and for this purpose the fingers 12 are provided with notches 26 arranged to be acted upon by the annular shoulder 25 to urge the fingers 12 outwardly. Similarly, the fingers 15 are provided with the notches 27 which are adapted to be acted upon by the annular shoulder 22 to urge the fingers 15 outwardly.

In addition to the configurations above described, the fingers 12 are provided exteriorly with the hook elements 28 and the cam surfaces 29 and interiorly they are provided with the hook elements 30. The last named configurations have to do with the attachment of the lowering tool and the lifting tool which will be described hereinafter.

The fingers 15 also have the external configuration of the slightly angular relation between the surfaces 31 and 32. This configuration has to do with the locking position of the fingers 15 which will be described hereinafter. These fingers also have their lower ends laterally beveled as indicated at 15a for a purpose which will be described later.

At its lower end, the body 10 is provided with an annular sealing abutment 33 and a central tubular extension 34. A member 35 having a central bore of a size to slip over the extension 34 is provided and is held in position by a collar 36 threaded on the end of the extension 34. The portions 34 and 35 are keyed together as shown. The member 35 has a reduced portion 37 and the rubber packers 38 and spacer

39 are disposed between the shoulder 35a on the member 35 and the annular abutment 33. The lower end of the member 35 is internally threaded as at 40 for the reception of the down-hole motor unit indicated generally in Figure 2 by the numeral 41. The details of the packing arrangement just described are more clearly seen in Figure 3. From the foregoing description it will also be clear that when the assembly has been lowered into the hole until the drill bit bottoms, the weight of the associated parts will produce a relative telescoping movement between the parts 34 and 35 which will compress the packers 38 and cause them to expand against the casing wall.

In Figure 1, there is shown a lowering tool 42. This tool may be secured to the end of a cable 43 and is provided at its lower end with a disc 42a providing an annular hook-like arrangement 42b. When it is desired to lower the assembly into the well casing, the body 10 with the down-hole motor and bit attached thereto is suspended from the tool 42 by engagement of the hook elements 30 of the fingers 12 over the annular hook element 42b of the tool 42. It will be understood that the fingers 12 must be pivoted inwardly manually and that thereby through action of the notches 26 of the fingers 12 against the shoulder 25, the spring 20 is compressed. By this action also the shoulder 27 is moved downward slightly so that the fingers 15 may assume the position of Figure 1. The weight of the assembly suspended from the tool 42 maintains the parts in the position of Figure 1.

As the assembly is being lowered down the hole through the well casing, the well casing serves to hold the fingers 15 in position where the notches 27 assist in maintaining the spring 20 under compression.

At the bottom of the hole at the end of the casing string there is provided a special casing section indicated generally at 44 in Figure 2. This special casing section is provided with axial slots 45 to accommodate the fingers 12 and a joining section 46 is threaded into the upper end of the section 44 to provide the annular shoulder 47. The section 46 is threaded at 48 so that it may be screwed into the next upper casing section. The special section 44 is also provided with the recess 49 for the reception of the fingers 15. The casing section 44a is screwed into the lower end of the section 44, and the upper end of the section 44a is configured as shown in Figure 7 to provide the angular surfaces or teeth 44b. When the section 44a is screwed into the section 44, the members 44b lie within the section 44 in the recess 49. As the fingers 15 engage the members 44b with their beveled edges 15a, the positioning device is rotated and oriented so that the fingers 12 may enter their slots 45. Eight slots 45 have been shown, and eight members 44b; however there are only four fingers 12 and four fingers 15. The number of fingers and slots may of course be varied if desired. The member 44a provides the lower shoulders 50 against which the lower ends of the fingers 15 may abut. The special section 44a is also slotted as at 51 for the passage of fluid through the member 34 and down into the hydraulic motor. The hydraulic motor indicated generally at 41 is screwed into the lower end of the positioning structure by means of the threads 40. It will not be described in detail since it is fully disclosed and claimed in an application of Wallace Clark, Serial No. 582,016 filed May 1, 1956, and also in a copending application filed October 30, 1957, now abandoned, bearing Serial No. 693,319, in the names of Wallace Clark and Harry Conrad. I have also shown an additional casing section 52 screwed onto the bottom of the section 44a and having the internal cam surface 53 to assist in collapsing the collapsible bit indicated generally at 54. The collapsible bit is the one described in my copending application, Serial No. 683,391, mentioned above.

When the assembly comprising the positioning tool of Figure 1 with the motor and bit attached thereto and

suspended from the lowering tool 42 as shown is lowered into the hole through the well casing, nothing obstructs its movement until the fingers 15 enter the annular space 49. The fingers 15 which are under some slight pressure from the spring 20, enter the recess 49 and upon contact with the members 44b they rotate the device to orient the fingers 12 with the slots 45, and then the shoulders 50 prevent further downward movement of the assembly. As soon as tension is removed from the cable 43, the spring 20 forces the plunger 18, 21, 23, upwardly to firmly thrust the fingers 15 outwardly and also to thrust the fingers 12 outwardly. These fingers then enter the slots 45 and the shoulders provided by the hook elements 28 thereof abut against the shoulder 47 of the member 46. This abutment locks the device against upward thrust and the entry of the fingers into the slots 45 locks the device against rotation. It will be noted that when the fingers 12 move outwardly, the lowering tool 42 becomes freed and can be lifted out of the hole. Fluid can then be pumped down the well casing, as diagrammatically indicated, to drive the down-hole motor and operate the bit.

When it is desired to lift the assembly out of the hole, a lifting tool is employed as shown in Figure 4. The lifting tool comprises a member 55 hollow as indicated at 56 and having the inwardly directed annular hook element 57. The internal walls of the hollow 56 are sloped as indicated at 58. The member 55 may be attached to a cable and when it is lowered into the hole the chamfered inner surface 59 of the lifting tool cooperates with the cam surfaces 29 of the fingers 12 to force the fingers 12 inwardly until the hook element 57 engages in the hook elements 28 heretofore described. This action, through the notches 26 and the shoulder 25, forces the member 23 downwardly compressing the spring 20 and removing the thrust from the fingers 15. The fingers 15 in their locked position are in the position shown in Figure 2 wherein their surfaces 32 lie substantially flush in the annular recesses 49. The surfaces 31 thus constitute cam surfaces so that as the assembly is raised, the fingers 51 will be forced inwardly, thus further compressing the spring 20 and permitting the fingers 15 to pass through the casing.

From the foregoing description, it will be seen that I have provided a device by means of which a down-hole motor can be positioned against upward, downward and rotational movement with respect to a special casing section at the bottom of a well and that I have provided simple means for lowering the device to its operative position and for lifting it out of its operative position.

It will be understood that various modifications may be made without departing from the spirit of my invention and I therefore do not intend to limit myself except as set forth in the claims which follow.

Having now fully described my invention, what I claim as new and desire to secure by Letters Patent is:

1. A structure for positioning a down-hole motor and drill in a well casing at the bottom of a hole, comprising a body of dimensions to pass through said casing, means on said body for the attachment of a motor to the lower end thereof, a set of upwardly extending fingers symmetrically disposed about said body and pivoted thereto at their lower ends, a set of downwardly extending fingers symmetrically disposed about said body below said upwardly extending fingers and pivoted to said body at their upper ends, a plunger axially slidably mounted in said body, spring means urging said plunger upwardly, said plunger having means abutting said upwardly extending fingers to urge them to swing outwardly, and also having means abutting said downwardly extending fingers to urge them to swing outwardly; and means at the upper ends of said upwardly extending fingers for alternatively attaching a lowering tool or a raising tool.

2. A structure according to claim 1, wherein said means for alternatively attaching a lowering tool or a raising

tool comprises, at the upper ends of said upwardly extending fingers, inwardly directed hook elements and outwardly directed hook elements, the upper ends of said upwardly extending fingers having cam surfaces leading outwardly toward said outwardly directed hook elements.

3. A structure according to claim 2 in combination with a lowering tool, said tool being attachable to a cable and having an annular outwardly directed hook member, said body being suspendable from said tool by the engagement of the inwardly directed hook elements of said fingers with said annular hook member, against the action of said spring means, and being disengageable by a slight lowering of said tool when said body is positioned in said casing.

4. A structure according to claim 2, in combination with a lifting tool, said tool being attachable to a cable and being generally bell-shaped and terminating in an annular inwardly directed hook element, said tool being engageable with said body by being lowered over said fingers, said inwardly directed hook element riding over said cam surfaces, causing said fingers to pivot inwardly until said last named hook element engages the outwardly directed hook elements on said fingers.

5. A structure according to claim 1, in combination with a casing section adapted to be installed at the lower end of a string of casing and having slots to receive said upwardly extending fingers, and orienting means arranged to coact with said downwardly extending fingers to rotate said body to insure the entry of said upwardly extending fingers into said slots.

6. A structure for positioning a down-hole motor and drill in a well casing at the bottom of a hole, comprising a body of dimensions to pass through said casing, means on said body for the attachment of a motor to the lower end thereof, a set of upwardly extending fingers sym-

metrically disposed about said body and pivoted thereto at their lower ends, a set of downwardly extending fingers symmetrically disposed about said body below said upwardly extending fingers and pivoted to said body at their upper ends, a plunger axially slidably mounted in said body, spring means urging said plunger upwardly, said plunger having means abutting said upwardly extending fingers to urge them to swing outwardly, and also having means abutting said downwardly extending fingers to urge them to swing outwardly; in combination with a casing section adapted to be installed at the lower end of a string of casing, said section having an annular recess providing a lower shoulder into which recess and against which shoulder said downwardly extending fingers may extend to lock said structure against downward movement, said section also having vertical slots symmetrically disposed thereabout and in number equal to said upwardly extending fingers and providing upper shoulders, into which slots and against which shoulders said upwardly extending fingers may extend to lock said structure against upward and rotational movement; and means at the upper ends of said upwardly extending fingers for alternatively attaching a lowering or a lifting tool.

7. A combination according to claim 6, wherein orienting means are provided in said annular recess and arranged to coact with said downwardly extending fingers to rotate said body to insure the entry of said upwardly extending fingers into said slots.
